(57) **CLAIM**

The ornamental design for an electric haircut clipper, as shown and described.

DESCRIPTION

FIG. 1 is a perspective view of an electric haircut clipper showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a charging base of the electric haircut clipper;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the electric haircut clipper shown with the charging base;

FIG. 18 is an enlarged view of portion 18 shown in FIG. 2;

FIG. 19 is an enlarged view of portion 19 shown in FIG. 4;

and,

FIG. 20 is an enlarged view of portion 20 shown in FIG. 7. The electric haircut clipper and the charging base have been shown separately in FIGS. 1-8 and 9-16 to show aspects of the design that are not visible when combined. The dash-dash broken lines in the drawings depict portions of the electric haircut clipper and the charging base of the electric haircut clipper that form no part of the claimed design. The dot-dash broken lines represent boundaries of the enlarged portions and form no part of the claimed design.

1 Claim, 20 Drawing Sheets
